(57) **CLAIM**

The ornamental design for a vest, as shown and described.

DESCRIPTION

FIG. 1 is a back perspective view of a vest, FIG. 2 is a back elevational view thereof, FIG. 3 is a top plan view thereof, FIG. 4 is a bottom plan view thereof, FIG. 5 is a front elevational view thereof; and, FIG. 6 is a right elevational view, the left side being a mirror image thereof.

The thick broken lines and the thin broken lines in the figures illustrate portions of the vest which form no part of the claimed design.

1 Claim, 4 Drawing Sheets
